U.S. Appl. No. 29/372,571, Applicant: Eun-Ha Choi, et al., filed Dec. 8, 2010 entitled Air Cleaner.

Primary Examiner — David Muller

(74) Attorney, Agent, or Firm — Flynn, Theil, Boutell & Tanis, P.C.

(57) **CLAIM**

The ornamental design for an air cleaner, as shown and described.

DESCRIPTION

FIG. 1 is a top front perspective view of an air cleaner showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environmental subject matter only and form no part of the claimed design.
